TOY TRIP HAMMER

Carl J. Olson, Racine, Wis.

Application October 10, 1935, Serial No. 44,411

3 Claims. (Cl. 46—39)

This invention appertains to toys, and more particularly to a novel toy trip hammer.

One of the primary objects of my invention is to provide novel means for raising the hammer 5 on each stroke of an operating lever, whereby the hammer will be quickly actuated as the lever is raised and lowered.

Another salient object of my invention is the provision of a tapered head carried by the operating rod of the hammer, with rocking arms adapted to alternately spring past the head and catch under the head for raising the hammer, the head being adapted to ride off of the arms when the hammer reaches its greatest height so 15 that the hammer will fall under its own weight and deliver the desired blow.

A further object of my invention is the provision of resilient means located in the path of the head, so that as the hammer and the head are raised, the spring member will be flexed, and thus give an initial downward impulse to the hammer as the head rides off of the rocking arms.

Another important object of my invention is to provide a toy trip hammer, which will present 25 a pleasing and attractive appearance, and closely simulate the action of a large trip hammer, and thereby give a maximum amount of pleasure to a child.

A still further object of my invention is to 30 provide a toy trip hammer, which will be durable and efficient in use, one that will be simple and easy to manufacture, and one which can be placed upon the market at a small cost.

With these and other objects in view, the 35 invention consists in the novel construction, arrangement, and formation of parts, as will be hereinafter more specifically described, claimed, and illustrated in the accompanying drawing, in which drawing:

40 Figure 1 is a front elevation of the toy, with one of the cover plates removed, parts of the frame being shown broken away and in section to illustrate the means for anchoring the return spring in place.

45 Figure 2 is a fragmentary side elevation of the toy, illustrating means of operatively connecting the rocking arms to the operating lever.

Figure 3 is a detailed vertical section, taken 50 on the line 3—3 of Figure 1, looking in the direction of the arrows.

Referring to the drawing in detail, wherein 55 similar reference characters designate corresponding parts throughout the several views, the letter "H" generally indicates my improved toy trip hammer, which comprises a supporting base

plate 5 having rigidly connected thereto the upstanding side standards 6 and 7. The lower ends of the standards 6 and 7 are slightly arched, as at 8, and receive therebetween the stationary anvil 9, which is rigidly secured to the upper face of the base plate 5. Above the anvil 9 the standards 6 and 7 are formed to provide a vertical guide 10 for the hammer 11. The hammer 11 is mounted for reciprocatory movement in the guide 10, and the hammer can be provided with guide 10 straps 12 for engaging the opposite faces of the standards 6 and 7.

The hammer has rigidly secured thereto the upstanding operating rod 13, which slidably extends through a guide plate 14 carried by the standards. The extreme upper end of the rod 14 has formed thereon, or secured thereto, an inverted V-shaped lift head 15, having oppositely inclined side edges 16 and abrupt bottom shoulders 17.

In order to bring about the quick and efficient raising and lowering of the hammer 11, I provide 20 rock arms 18 and 19, which are disposed on opposite sides of the rod 13 and its head 15. The arms 18 and 19 are in the nature of bell cranks, and 25 are pivoted at their angles on a transversely extending shaft 20 carried by the standard 7. This standard 7 is slotted, as at 21, to receive the arms, and the arms are formed relatively thin and of a 30 resilient nature so that the same will flex, for a purpose which will be later set forth.

The extreme outer ends of the arms 18 and 19 have pivotally connected thereto depending links 22 and 23, the lower ends of which are pivotally connected, as at 24, to an operating lever 25 on 35 the opposite sides of its pivot 26. The pivot 26 is anchored to the standard 7 adjacent to the lower end thereof, and the outer end of the lever 25 is extended (not shown) to form an operating handle. Referring again to the rock arms 18 and 40 19, it is to be noted that the inner ends thereof have formed thereon arcuate extensions 27, which are adapted to engage under and ride from beneath the head 15 of the rod 13.

In operation of my improved toy, the operating 45 lever 25 is raised and lowered by the child, and the hammer will be raised both on the up stroke and down stroke of the lever. As the lever 25 is actuated, the arms 18 and 19 will be alternately raised and lowered. As one of the arms 18 or 19 50 is lowered, its bottom edge will ride on an inclined side 16 of the head 15, and the arm will be flexed and ride past the head. When the hammer reaches its extreme height, the arm which is elevating the hammer will ride from 55

under the head 15, and allow the hammer to drop against the anvil under its own weight. As the hammer falls, and the lever 25 is again actuated, the arm, which was brought to a lowered position, will engage one of the abrupt shoulders 17, and lift up the head 15, the rod 13, and the hammer 11, and as the head raises the other arm will spring past the head and move to a lowered position. Thus, as the arm, which is 10 raising, rides from under the head, the hammer will fall, and the lowered arm will be in position for again raising the hammer.

If so desired, I can provide a leaf spring 30 arranged in the path of the head 15, so that 15 when the head is raised the spring 30 will be flexed, whereby when an arm rides from under the head the spring will exert an initial impulse for moving the hammer down.

As shown, the ends of the spring 30 are set 20 cured to the standards 6 and 7, and are held in place by a top wall 31. Front and rear plates 32 and 33 can be secured to the standards 6 and 7 so as to form a closure for the operating parts of the hammer.

25 Changes in details may be made without departing from the spirit or scope of my invention, but what I claim as new is:

1. A toy comprising a frame, a hammer reciprocatively mounted in said frame having a substantially V-shaped head provided with inclined 30 sides and abrupt bottom shoulders, a pair of rock arms mounted on the frame disposed on opposite sides of the head and adapted to spring past said head and under said shoulders, means for alternately operating said arms, and a spring disposed in the path of said head for giving an initial impulse thereto.

2. A toy comprising a frame, a hammer slidably mounted in said frame, an anvil carried by

the frame disposed below the hammer, an operating rod secured to the hammer, an inverted V-shaped head on said rod having oppositely inclined sides and abrupt bottom shoulders, rock arms of a bell crank shape rockably mounted at 5 their angles on the frame, the inner ends of the rock arms being provided with flexible arcuate extensions adapted to flex past said head and under the shoulders upon downward movement thereof, said arms being adapted to ride from 10 under the shoulders upon upward movement of the arms and hammer when the arms and hammer reach a predetermined position, an operating lever rockably mounted on the frame, and links operatively connecting the outer ends of 15 the rock arms with the lever on opposite sides of its pivot.

3. A toy comprising a frame, a hammer slidably mounted in said frame, an anvil carried by the frame disposed below the hammer, an operating rod secured to the hammer, an inverted 20 V-shaped head on said rod having oppositely inclined sides and abrupt bottom shoulders, rock arms of a bell crank shaft rockably mounted at their angles on the frame, the inner ends of the 25 rock arms being provided with flexible arcuate extensions adapted to flex past said head and under the shoulders upon downward movement thereof, said arms being adapted to ride from 30 under the shoulders upon upward movement of the arms and hammer when the arms and hammer reach a predetermined position, an operating lever rockably mounted on the frame, links operatively connecting the outer ends of the rock 35 arms with the lever on opposite sides of its pivot, and a leaf spring disposed in the path of the head and adapted to be flexed by said head when the head reaches its extreme raised position.

CARL J. OLSON.
